UNITED STATES PATENT OFFICE.

EUGÈNE SCHNEIDER, OF PARIS, FRANCE, ASSIGNOR TO SCHNEIDER & CIE., OF PARIS,
FRANCE, A LIMITED JOINT-STOCK COMPANY OF FRANCE.

APPARATUS FOR SETTING TIME-FUSES.

1,343,588.

Specification of Letters Patent. Patented June 15, 1920.

Application filed June 16, 1919. Serial No. 304,657.

To all whom it may concern:

Be it known that I, EUGÈNE SCHNEIDER, a citizen of the Republic of France, residing at 42 Rue d'Anjou, Paris, France, have invented new and useful Improvements in Apparatus for Setting Time-Fuses, which invention is fully set forth in the following specification.

This invention has for its object to provide an improved setting apparatus for the known type of time fuses wherein the fuse composition is wound in the form of a helix around the body of the fuse, the distance at which the shell-exploding mechanism is to operate being determined by the point where a vent is pierced, said point being more or less close to the beginning of the fuse cord.

The improved fuse-setting apparatus is more particularly designed to be capable of being permanently fitted to the gun, for instance by means of a bracket fixed to one of the gun cradle trunnions. In these circumstances the improved fuse-setting apparatus is intended to be employed for setting fuses carried by shells placed on a loading truck or a loading trough, the shell remaining stationary upon the said trough during the whole of the setting operation, and the engagement of the fuse-setting apparatus upon the ogival nose of the shell being effected by a relative displacement between the trough and the fuse-setting apparatus.

The improved fuse-setting apparatus comprises in the known manner a box wherein the ogival nose of the shell engages in a correspondingly shaped lodgment. This box is combined with a socket in which the fuse is adapted to engage and which can be rotated around its longitudinal axis, the said socket serving as a support for the punch that pierces the vent.

According to this invention the punch-holder may be brought opposite the desired place of the fuse cord without it being necessary to shift the shell. For this purpose the rotational movement of the punch-holder socket being combined with the longitudinal displacement of the said punch-holder upon this socket; this longitudinal displacement taking place along a suitable guide.

In practice, this result is effected in a simple manner by providing on the box in which the shell engages, a row of bevel teeth over which rolls a bevel pinion keyed on an axle journaled in the socket. This axle has

a screw-threaded portion along which is adapted to move by means of an internal screw-thread, the punch-holder carriage which is itself guided longitudinally along the said socket. 60

The invention comprises also a safety device for preventing the displacement of the punch in the punch-holder so long as the fuse is not completely engaged in the socket; this arrangement avoids any error and any wrong movement in the operation of piercing the vent. 65

Various constructional forms of this invention are illustrated by way of example in the accompanying drawings in which: 70

Figure 1 is a vertical longitudinal section of a first constructional form on the line I—I of Fig. 2.

Fig. 2 is a plan partly in section on the line II—II of Fig. 1. 75

Fig. 3 is an end elevation viewed from the left of Figs. 1 and 2, in partial section on the line III—III of Fig. 1.

Fig. 4 is a partial cross section on the line IV—IV of Fig. 1. 80

Figs. 5 and 6 are partial sections corresponding respectively to Figs. 1 and 2; they show the parts of the mechanism in the positions they occupy before the shell is engaged in the improved apparatus. 85

Fig. 7 is a partial vertical section of a modification of the mechanism for actuating the punch-holder socket and the graduated drum that serves for regulating the position of the punch. 90

Fig. 8 is a vertical longitudinal section of a modification of the mechanism for operating the punch. 95

Figs. 9, 10 and 11 are sections respectively on the lines IX—IX, X—X and XI—XI of Fig. 8.

The improved fuse-setting apparatus comprises a box A whose inside wall *a* is shaped in profile to correspond with the shape of the ogival nose B of the shell. This box is 100 preferably provided externally with a tenon A¹ for guiding it in a bracket C formed on a part of the gun carriage, for instance on one of the gun cradle trunnions D.

The inside wall *a* is formed at its end 105 with a guide groove *a*¹ for a tenon *e* of the fuse body E.

A drum F arranged along the longitudinal axis of the said box, is held in a groove in the wall *a*, and it is provided at its end 110

with a socket f . The combination $F-f$ is capable of being rotated around its own axis, for which purpose the drum F has a ring of teeth F^1 meshing with a bevel pinion G that is keyed on an axle g journaled in the box A .

H is a punch-holder carriage adapted to receive a helical motion intended to bring the punch I at will opposite any one of the 10 points of the wall of the casing e^1 that encloses the fuse cord e^2 .

For this purpose the carriage H is mounted by means of an internal screw-thread h upon the screw-threaded portion 15 of an axle J and journaled in the lodgments formed on the punch-carrying socket $F-f$. One of these lodgments is, as shown in the drawings, formed in the end of the drum F , while the other lodgment is formed in a 20 bracket f^2 projecting from the socket proper f .

The carriage H is guided longitudinally, preferably on an axle K parallel to the screw-threaded axle J , situated symmetrically to the latter in relation to the longitudinal axial plane of the apparatus. This axle performs also a further function in the safety device hereinafter described.

The longitudinal displacement of the carriage H along the screw-threaded axle J and along the axle K is imparted to it by a rotational motion of the socket by means of a bevel pinion J^1 fixed on the said axle J and rolling over a ring of teeth a^2 formed on the 35 outside of the wall a .

Externally, the drum F bears a scale arranged in helical lines which are caused by the rotational motion imparted to the socket, to appear at a window l formed in a screen 40 L . This screen which is of cylindrical form, is guided by its longitudinal edges L^1 , L^2 in the fixed box A , while it engages by means of a tenon L^3 in a helical groove F^2 cut in the drum F along the scale carried by 45 the latter.

The ratio between the number of teeth of the pinion J^1 and of the ring of teeth a^2 , and the pitch of the screw-thread of the axle J , must of course be so selected that the 50 punch will move always opposite the fuse cord e^2 .

The socket f is pierced with an aperture f^1 that allows the punch I to pass through for setting the fuse. A spring i has a constant tendency to keep the punch I out of 55 the way in the lodgment reserved for it in the carriage H .

The said carriage constitutes on the other hand a bearing for an axle h^1 upon which is 60 fixed a cam h^2 designed to cause the movement of the punch for the purpose of setting the fuse. On the same axle are keyed the operating levers M that are connected together by a handle m .

According to this invention the displace-

ment of the punch I in its lodgment is prevented so long as the shell B provided with its fuse E , is not completely engaged in the fuse-setting apparatus. For this purpose a spring-pusher member $N-n$ is arranged in 70 the end of the socket f , the spring n having a constant tendency to push the said member inward into the position shown in Fig. 5.

The said spring-pusher member carries 75 projecting laterally therefrom a stud n^1 engaging with a certain amount of "play" in a buttonhole-slot of a link O pivoted to the socket f .

The free end of the link O is forked, the limbs o of the fork inclosing between them 80 a tenon p projecting from a slide block P . The latter is slipped on the axle K and is held by means of a projection p^1 in a helical groove k formed in the said axle.

It will be clearly perceived that a longitudinal movement of the spring-pusher N will cause a rotational movement of the link O driven by the stud n^1 . This rotational movement of the link produces in its turn by means of a movement of the projection p^1 in a helical groove k 85 formed in the axle K , a longitudinal movement of the nut P , causing thereby a rotational motion of the axle K .

On this axle K there is adapted to slide 90 an eccentric Q which is provided for this purpose with a projection q movable in a groove k^1 in the axle K . The eccentric Q is also held in the carriage H , so that it will move longitudinally with the said carriage. The rotational motion of the eccentric produces a longitudinal movement of a stop R 95 guided in the carriage H . The punching movement of the punch will be free to take place or will be prevented according as this stop occupies the position shown in full 100 lines in Fig. 3, which corresponds to the complete inoperative position of the spring-pusher member N (Fig. 1) or a position intermediate between the latter position and the position indicated in dot and dash lines 110 in Fig. 3. So long as the stop R is not completely inoperative it will act as a stop for a tappet I^1 projecting from the head of the punch I .

For setting the fuse, the operation is as 115 follows: The operator actuates a hand-wheel S after releasing its spring handle s that is normally engaged in the teeth of a disk A^2 carried by the box A . This causes a rotation of the pinion G and consequently 120 of the drum F and the socket f together.

In this movement, the pinion J^1 rolls over the ring of teeth a^2 with the result of moving the punch-holder carriage H along the screw J and the guiding axle K . The whole 125 combination $F-f-H-M-n$ will then turn around the longitudinal axis of the apparatus, while the punch is moving longitudinally in front of the aperture f^1 .

The rotation of the graduated drum F 130

causes also as above stated, a longitudinal movement of the screen L, the window in the said screen showing only a portion of the scale on both sides of a register mark L⁴ marked on the said screen. When the chosen scale division corresponding to the distance for which the fuse is to be set, comes opposite the register mark L⁴, the motion of the hand-wheel S is stopped by snapping the handle s back into the disk A².

Before the introduction of the shell, the spring-pusher member N—n occupies the position shown in Fig. 5, and the stop R is thereby engaged under the tappet I¹ of the head of the punch.

When, on engaging the shell in the fuse-setting apparatus, the fuse E has been inserted right home in its lodgment in the socket, this very fact will have moved the spring-pusher member N and caused a rotational movement of the link O, as well as a corresponding rotational movement of the axle K and the eccentric Q. The result is to move the stop R out of the way which thus returns into the position shown in Figs. 2 and 3.

The punch I will then be exactly opposite the desired point of the fuse cord, and the setting operation can be effected by operating the lever M by means of a handle m, which movement by rotating the axle h¹ and the cam h², causes the punch to pierce the fuse.

The graduated drum F may, for the purpose of facilitating the reading of the scale, be constituted by an independent part of the socket f carrying the ring of teeth F¹. In this construction, shown in Fig. 7, this drum may be provided with a ring of teeth F³ comprising fewer teeth than the ring of teeth F¹, and the drum may be actuated by a pinion G¹ of smaller diameter than the pinion G. While the socket f carrying the carriage H will make one complete revolution, the drum F will then make only a partial revolution.

Figs. 8-11 illustrate a modification. In those figures only the modified parts of the improved apparatus are shown in detail. In this modification the axle h¹ carrying the cam h² for actuating the punch I, instead of being carried by the carriage H, is carried by a carriage T sliding in a guide f⁴ formed on a bracket f² projecting from the lodgment of the pusher member N. The cam h² is formed on the end of one of the arms of a bell crank lever, the other arm h³ of which ends in a fork between the limbs of which are engaged two studs u projecting from a nut U mounted on a screw V.

The square head v of this screw is guided in a lodgment a³ of corresponding shape formed in a box A³ fixed to the box A.

A cylindrical tail N¹ projecting from the center of the pusher N, is guided in an axial

recess of the screw V. The head v of the screw V carries two studs v¹ that are constantly engaged in the forks w¹ of two small levers w fixed on an axle W journaled in the box A³.

The operating lever M is fixed on the same axle.

It will be perceived that on moving the lever M in the direction of the arrow (Fig. 8), the axle W and the small levers w will be caused to rock slightly and thereby move the studs v¹, and consequently the screw v and the nut U, thereby causing the rotation of the axle h¹ and cam h².

The advantage of this modification consists in this that the operating lever M is not affected by the rotational movements of the punch-holder carriage around the axis of the apparatus.

On the other hand the circumstance that the operating lever M is not affected allows of simplifying the safety device by means of which it is rendered impossible for the punch I to operate so long as the fuse E is not engaged right home in the socket f.

As shown more particularly in Figs. 8 and 11, the tail N¹ is formed at its downwardly bent point with a stop N² which, so long as the pusher N has not been forced right home by the fuse E, will be situated in the path of a finger m¹ formed on an arm M¹ carried by or fixed on the axle W.

What I claim is:—

1. Apparatus for setting helix wound projectile fuses, comprising a casing adapted to be mounted on the gun carriage and to receive the ogival nose of a projectile, said casing having a fuse setting socket revolvably mounted thereon and in axial alinement therewith, means revoluble with said socket for indicating fuse setting distances, a manually operated fuse punch carried by said socket and means operated by the rotation of said socket for registering the punch over the fuse as the socket rotates.

2. Apparatus for setting helix wound projectile fuses, comprising a casing adapted to be mounted on the gun carriage and to receive the ogival nose of a projectile, said casing having a fuse setting socket revolvably mounted thereon and in axial alinement therewith, means revoluble with said socket for indicating fuse setting distances, a manually operated fuse punch carried by said socket, means operated by the rotation of said socket for registering the punch over the helical fuse as the socket rotates and spring pressed means for rendering the punch inoperative when the fuse is not completely engaged in said socket.

3. Apparatus for setting helix wound projectile fuses, comprising a casing adapted to be mounted on the gun carriage and to receive the ogival nose of a projectile, said casing having a fuse setting socket revolvably

mounted therein and in axial alinement therewith, a drum provided with a distance indicating scale, means for simultaneously rotating said socket and scale drum, a fuse 5 punch carried by said socket and means operated by the rotation of said socket for registering the punch over the helical fuse as the socket rotates and spring pressed means for rendering said fuse punch inoperative 10 when the fuse is not completely engaged in said socket.

4. Apparatus for setting helix wound projectile fuses, comprising a casing adapted to be mounted on the gun carriage and to receive the ogival end of a projectile, said casing having a fuse setting socket revolvably mounted thereon and in axial alinement therewith, a threaded shaft mounted on said socket in a plane through the longitudinal 20 axis thereof, a punch-holder mounted on said socket provided with a manually operated fuse punch and having threaded engagement with said shaft, a guide member supporting said carriage, means for simultaneously rotating said socket and shaft whereby the punch is made to follow said fuse as the socket rotates and spring pressed means normally in the path of said punch-holder to prevent its operation and adapted 25

to be withdrawn on proper insertion of the fuse in said socket.

5. Apparatus for setting helix wound projectile fuses, comprising a casing adapted to be mounted on the gun carriage and to receive the ogival end of a projectile, said casing having a fuse setting socket revolvably mounted thereon and in axial alinement therewith, a threaded shaft mounted on said socket in a plane through the longitudinal axis thereof, a rack on the body portion of 40 said casing having engagement with said threaded shaft, a fuse punch-holder having threaded engagement with said shaft, a revolute guide member having slidable engagement with said holder and provided with a 45 cam operated punch locking member adapted to move in and out of the path of said punch, spring pressed means controlled by the proper insertion of the fuse in said socket for operating said cam through said 50 guide member and means for rotating said socket.

. In testimony whereof I have signed this specification.

EUGÈNE SCHNEIDER.
